TIME SWITCH

Frank A. Ward, Baltimore, Md.

Application April 6, 1945; Serial No. 586,845

2 Claims. (Cl. 200—39)

1

This invention pertains to electrical switches and more particularly to automatic clockwork switches.

In the conventional types of automatic switches it is customary to set the switches to open or close at a definite clock time of relatively long spacing periods apart. They are not made or intended to be used for a setting one minute away, or some similar short period. They are not sensitive enough for such operation and their general use is for periods of much longer duration.

The object of this invention is to provide a new and improved type of automatic clockwork switch that will operate on relatively short-period settings, and avoid one or more of the disadvantages and limitations of the prior art.

Another object of this invention is to provide a new and improved clockwork switch that may be used either automatically or as an ordinary switch.

Other objects will become apparent as the invention is more fully set forth.

In particular form of this invention, as indicated in the drawings:

Figure 1 is a top view of an automatic time switch embodying this invention.

Figure 2 is a front view of Figure 1.

Figure 3 is right end view of Figure 1.

Figure 4 is a back view of Figure 1.

Figure 5 is a sectional view taken along lines 5—5 of Figure 3.

Figure 6 is a sectional view taken along lines 6—6 of Figure 3, revolved clockwise 180° and

Figure 7 is a view showing pawl and control element looking in direction of arrows 7—7 of Figure 1.

Similar reference characters refer to similar parts throughout the drawings.

In the drawings, 10 represents a switch wall face plate having a slot 11 in which a button 12 moves in a reciprocating manner in accordance with the opening and closing of the switch. A small slide 13 is provided under the button 12 to keep the latter from slipping through the slot 11, and an underslide 14 is mounted on the opposite side of the face plate and attached to the button to react in the opposite manner and thereby keep the button in position on the face plate. An extension piece 16 is mounted on the underslide 14 to be moved in coordination with the reciprocating movement of the button. Pins 15 and 17 are secured to this piece 16 for operating the mechanism to be described, one being above on one side while the other is below on the opposite side of the piece. The setting mechanism

2

is also mounted on the front of the face plate 10, and consists of a knurled nut 50 which a pointer 51 is attached. Indices 52 are engraved in the front of plate 10 on an arc for the pointer 51 to point to as it is rotated to different settings. A shaft 53 attached to the nut passes through the plate, is journalled in bearing members 22 and has a pawl 23 mounted near its end for engagement in a clockwork control element 24. The pawl has several teeth 25 for holding the control element in various periods of setting. The pin 17 attached to the rear of extension piece 16 contacts shoulder 19 of lever 21 and withdraws the face 76 thereof and allows the pin 27 attached to the rear of operating plate 28 to travel a predetermined distance, this allows the face 77 of lever 20 to contact the pin 27 and hold same in place. In this position the switch contact is closed. When the pointer 51 points to 0, and the button 12 is pushed to the "on" position, the pin 17 contacts the shoulder 18 of lever 20 and withdraws the face 77 which allows the pin 27 and operating plate 28 to move and open the switch. The levers 20 and 21 are attached by pins 47 and 48 to back plate 30 and tensioned by springs 62 and 63 respectively. When the pawl 23 is set for a time delay in opening the switch contacts, the pin 17 contacts shoulder 19 as outlined above, the button 12 is then pushed to the left and the pin 17 contacts the shoulder 18. During this cycle a hook 78 on catch 40 drops down and holds underslide 14 in its normal "off" position until the switch contacts open. The catch 40 is attached to the face plate 10 by a pivot 42 and tensioned by a spring 43 to keep the hook 78 ready to engage the underslide 14 when the pointer is not set to "0" open and closed switch contacts. The hook 78 is disengaged from contact with the underslide 14 when pin 39 attached to operating plate 28 contacts the end 41 of catch 40. The operating plate 28 rotates arcuately on a shaft 29 which extends out from the back plate 30 of the frame that holds the various mechanisms and face plate of the device. Mounted loosely and arcuately on the same operating plate 28 are a pair of bowed arms 32 and 33 which are pivotally attached to the plate 28 by pins 54 and 55 and are resiliently tensioned by a spring 31 to pull towards each other. This is done so the movement of the arm 32 in one direction will pull on the spring 31 and arm 33 and pull the operating plate 28 towards the arm 32. The plate 28 however will not move under these pulls until it is released. The other ends of the bowed arms 32 and 33 are bent to form projection 66 and 67 which are contacted

by pin 15 attached to extension piece 16. The control element consists of a cam 34 which is mounted loosely on the shaft 29, and is attached to one end of the control element 24 by a pin 59 and is rotated back and forth in an arcuate path, depending upon the position of the pawl 23, against the end 58 of the element 24. The element 24 is supported at one end by a pin 57 which is supported on back plate 30 and operates in an elongated slot 56. The element 24 is tensioned against the pawl 23 by a spring 68 attached at the end to a pin 89, and at the other by the pin 57. The contact part 75 of the cam 34 is set in a predetermined position through the adjustment of the knurled knob 59 and pawl 23. When the pawl 70 which is pivotally attached to the operating plate 28 by a pin 69 and tensioned by a spring 73 contacts the cam 34 through its pin 71 it lifts the contact point 72 of the pawl 70 out of contact with the teeth 35 of a ratchet gear 36 and allows the operating plate 28 to return to its normal position as shown in Figure 1. While the pawl 70 is engaged with the ratchet gear 36 it connects the operating plate 28 rigidly with it, and the gearing 38 and clock mechanism. The control element 24 operates the cam 34 and this in turn controls the position of the pawl 70 and its engagement in the gear 36. The operating plate 28 has a groove 44 provided in its periphery at a predetermined point, which serves to engage another pin 45 when it is rotated around to it. This pin connects with a bell crank 46 mounted on the back of the face plate 10 by a pin 81 and has an insulated block 49 for engaging the contact means 79 of the switch, and forcing them together when the pin 45 is out of the groove 44 and releasing them when the pin 45 is in the said groove 44. The movement of the operating plate 28 is controlled by a pin 82 contacting stops 83 and 84. The clockwork or horological mechanism 37 of the device used as a motor to operate the switch structure of the invention is of conventional design and fastened to the back plate 30 of the switch. It is preferably of the alarm clock type including a train of gears 60 operated by a spring that has been wound up in an amount equal to the setting of the time delay pointer 50 to give the necessary operative tension. A secondary train of gears 38 is actuated by the first train of gears 60. In the form shown, the switch is a single pole type, but may be varied to suit. In the operation of the device, assuming it to be connected up to a lighting circuit, such as a porch light, and the operator desires to use the switch as an ordinary switch. He sets the indicator to instantaneous, and throws his switch to the "on" position, the light will light, and when he throws the switch to the "off" position the light will immediately go out. If the operator desires to use the switch with time delay circuit opening, he turns the pointer until it is set for one, two or three minute operation. The button 12 is then moved to the "on" position and the light will go on. When the operator desires to leave the house, he merely pulls the button 12 in the other direction until the switch is in the "off" position and the light will remain on until the time set elapses and the switch will open and put out the lights. During the manipulation of the button 12 to the "on" and "off" position while the delay circuit opening is set the mechanism functions as follows: When the button 12 is pushed to the "on" position the pin 15 contacts the projection 67 forming part of arm 33 and

through the tension of spring 31 pulls the operating plate 28 to the right, this causes the bell crank 46 to move and close the switch contacts. The pointer 50 is then set to the selected time delay and the button is pulled back to the "off" position, but the light remains lighted until the contacts open. During the time interval while the button 12 is being moved back, the catch 40 holds the underslide 14 and button 12, the pin 15 forces the arm 33 outwardly and through the tension of spring 31 causes the operating plate to move the ratchet 36 and gearing 38 and clock mechanism, the setting of the pointer, controls the setting of the cam 34 and will cause the operating plate to return to its starting position, the pin 39 will strike the catch 40 and release the underslide 14, the pin 45 will be in the groove 44 and the contact 79 will be open. The particular use of the switch is in connection with any installation where it is desired to turn a switch off and have its opening period delayed. Such a use may be in connection with residences where it may be desired to leave the light on the porch for a short period of time after the person leaves the house, and then have it go out automatically, in order that the resident may not be compelled to return to turn the switch off. For example, the owner may want to leave the house and enter an automobile and while doing so have the light remain on, but by the time he has driven off, and the light is not needed, the switch may operate to turn the light off for him. Then the switch will be left in condition for normal operation, and ready at any time to be used for the same operation as desired.

While but one general form of the invention is shown in the drawings and described in the specifications, it is not desired to limit this application for patent to this particular form or in any other way otherwise than limited by the scope thereof, as it is appreciated that other forms of construction could be made that would use the same principles and come within the scope of the appended claims:

Having thus described the invention; what is claimed is:

1. A combined electrical and time delay switch comprising in combination, a face plate having an elongated slot therein, a back plate positioned at right angles to said face plate and having a slot therein, switch contacts mounted on one side of said back plate, a bell crank mounted on one side and projecting through the slot in said back plate to open said switch contacts at predetermined intervals, an operating plate comprising stops and a groove therein, a pin positioned on said back plate to limit the movement of the operating plate in opening and closing said contacts, a plurality of bowed arms pivotally attached to said operating plate and rotated thereby, spring means for tensioning said bowed arms, a cam positioned on said back plate, an element connected to said cam a pawl positioned on a shaft having a knob and pointer for positioning said element and cam, and a button reciprocating in said face plate and having pins projecting therefrom, said pins periodically contacting said bowed arms for winding the time delay opening means for opening or closing the switch contacts at predetermined intervals.

2. A combined instantaneous and time delay electrical switch comprising in combination, a face plate having a slot therein, a button reciprocating in said slot, a slide positioned under the

button and moving therewith, an underslide having an extension piece at right angles mounted on the opposite side of the wall plate and connected with said slide and button, said extension having pins projecting therefrom, a knob having a pointer positioned on said face plate, a shaft attached to said knob and having a pawl attached thereto for timing the mechanism, a plurality of levers having shoulders thereon, one of the pins attached to said underslide extension piece for actuating said levers, an operating plate having a pin attached thereto for contacting said levers, spring means for said levers, a combined hook and catch plate pivotally attached to said face plate, means for tensioning said hook and catch on said face plate, a pin attached to said operating plate for contacting the end of catch plate and releasing said hook, a back plate projecting from said face plate, a shaft projecting through said back plate for supporting the operating plate on one side and a cam on the other, a plurality of bowed arms pivotally mounted on said operating plate, tensioning means for said bowed arms, the lower ends of said bowed arms

bent to form a bearing plate for contacting one of the pins attached to said underslide extension piece, said cam mounted on a shaft and rotated in an accurate manner depending on the position of said pawl against the end of the element and setting of said pointer, a ratchet gear, a pawl pivotally attached to said operating plate for contacting said ratchet gear and rigidly connecting the operating plate and gear together at predetermined intervals, means for raising said pawl from the ratchet gear teeth, and means for controlling the travel of said operating plate.
